ATTORNEY

UNITED STATES PATENT OFFICE.

THOMAS HILL, OF JERSEY CITY, NEW JERSEY.

AXLE-BOX FOR VEHICLE-WHEELS.

SPECIFICATION forming part of Letters Patent No. 739,415, dated September 22, 1903.

Application filed February 16, 1903. Serial No. 143,477. (No model.)

To all whom it may concern:

Be it known that I, THOMAS HILL, a citizen of the United States, and a resident of Jersey City, in the county of Hudson and State of New Jersey, have invented certain new and useful Improvements in Axle-Boxes for Vehicle-Wheels, of which the following is a specification.

The invention relates to improvements in vehicle-wheels, and pertains more especially to the hub portion of the wheel; and the said invention consists in a novel tubular axle-box to be driven into the hubs of wheels and to receive the end of the axle.

Heretofore the hubs of vehicle-wheels have been provided with a tubular sleeve or box to be driven into the hub of the wheel and there secured by wedging and otherwise; but as heretofore constructed these tubular sleeves or axle-boxes have proven to be deficient in many particulars, more especially in the means and methods for securing them in place, and my invention pertains to this feature of a vehicle-wheel and consists in the novel axle-box hereinafter described and claimed adapted to be driven into the hub of a wheel and to be there secured in a very efficient manner. The axle-box of my invention is provided on its exterior surface with a series of flutings or longitudinal grooves, and in its preferred form the diameter of the box through the base of opposite grooves is somewhat less in diameter than the diameter of the entering end of the box, while the diameter of the said box through the apex of opposite ridges between the grooves is somewhat greater in diameter than the diameter of the entering end of the box.

The invention will be fully understood from the detailed description hereinafter presented, reference being had to the accompanying drawings, in which—

Figure 1 is a central vertical longitudinal section through an axle-box constructed in accordance with and embodying the invention, this axle-box being shown in position in the hub of a wheel, said hub being indicated by dotted lines. Fig. 2 is a detached side elevation of same. Fig. 3 is a vertical transverse section of same on the dotted line 3 3 of Fig. 2. Fig. 4 is a vertical transverse section, partly broken away, through the axle-box and hub on the dotted line 4 4 of Fig. 1.

Fig. 5 is a side elevation, partly in longitudinal section, of a modified form of axle-box embodying my invention, the modification consisting simply in tapering the outer end of the box instead of providing the same with the head shown in Fig. 2; and Fig. 6 is a vertical transverse section of same on the dotted line 6 6 of Fig. 5.

In the drawings, 10 designates the axle-box of my invention, and 11 the usual hub of a wheel, said hub being provided with a longitudinal bore 12 to receive the box 10. The axle-box 10 is of tubular form, as shown, and is to be driven into the bore 12 of the hub 11.

The novel feature of the box 10 is in the formation of the exterior surface thereof, this surface being slightly tapered and provided intermediate its ends with the series of longitudinal grooves 13, whose left-hand ends gradually merge into the smooth exterior surfaces of the box and whose right-hand ends, in the form shown in Figs. 1, 2, and 3, terminate at the base of the head 14, which in practice sets into the end of the hub 11. Intermediate the grooves 13 are the cone-shaped ridges or flutings 15, which preferably follow the general tapered outline of the box 10 and which in cross-section, due to the concave form of the grooves 11, are of cone shape. In the preferred construction of the box 10 the diameter of the box through the base of opposite grooves 13 is somewhat less than the diameter across the entering or left-hand end of the box 10, while the apex of the ridges or flutings 15 follow the uniform taper of the exterior of the box.

In the employment of the invention the box 10 is driven into the bore 12 of the hub 11, it being necessary that there should be a very tight fit of the box in said bore. In accordance with my invention the driving of the box 10 into the hub 11 effects the very important result of locking the box in position both against rotation and longitudinal displacement, and this is accomplished by reason of the grooves 13 and ridges or flutings 15. When the box 10 is driven into the hub 11, the ridges or flutings 15 will be crowded into the wood of the hub 11 and cause a displacement of a portion thereof into the grooves 13, the wood of the hub being displaced laterally along the opposite edges of the ridges

or flutings 15 and entering said grooves 13, where it will serve to form a number of locks to hold the box 10 against rotation and also against longitudinal displacement. The presence of the grooves 13 and ridges 15, without regard to the diameter of the box through opposite grooves with respect to the diameter of the entering end of the box, would prevent any rotation of the box within the hub 10 and also aid in preventing the longitudinal displacement of the box; but when the diameter through the base of the opposite grooves 13 is less than the diameter of the entering end of the box and the wood of the hub is forced into said grooves it will be seen that the wood lying within the grooves serves to lock the box against longitudinal displacement, since the diameter of the bore of the hub at the base of the opposite grooves then becomes less than the diameter of the entering end of the box 10, and it is one of the purposes of my invention that the wood of the hub 11, at the intermediate portions of the bore 12, shall be displaced inwardly, so as to reduce the diameter of said bore, and thereby prevent the longitudinal displacement of the box 10. The bore 12 may be formed in the usual manner in the hub 11, and hence there is nothing new in the hub 11 itself, my invention pertaining solely to the construction of the box 10, the outer surface of the latter being so formed that when driven into the hub 11 it will become locked against both rotary and longitudinal movement.

35 My invention dispenses entirely with all of the usual means employed for locking axle-boxes in their hubs and is not only for this reason of great advantage, but it is also of substantial benefit, because by reason thereof the axle-box becomes more efficiently locked in position than has heretofore been possible with the means heretofore known for that purpose.

40 In Fig. 5 I illustrate an ordinary form of axle-box with my invention embodied therein,

this box being provided with the grooves 13 and ridges or flutings 15, but having a tapered outer end instead of being provided with the head 14. (Shown in Fig. 2.) I prefer the employment of the head 14 on the axle-boxes 10, 50 but am aware that in some localities it is customary to taper the outer ends of the boxes, and therefore I present the illustration shown in Fig. 5, so as to indicate that my invention is applicable both to axle-boxes having the head 14 and to axle-boxes having a tapered outer end. 55

What I claim as my invention, and desire to secure by Letters Patent, is—

1. In combination with the wooden hub of 60 a vehicle-wheel, the axle-box tapered on its exterior intermediate its ends and along said tapered portion having the longitudinal grooves and the longitudinally-tapered ridges or flutings intermediate said grooves and 65 adapted to be pressed into the wood of the hub, said grooves being disposed to receive the wood of the hub displaced by said ridges or flutings when the box is driven into the hub; substantially as set forth. 70

2. The axle-box for wheel-hubs, said box having a tapered exterior surface and over said surface having the longitudinal grooves between which are the longitudinally-tapered ridges or flutings adapted to be pressed into 75 the wood of the hub, said grooves being disposed to receive the wood of the hub displaced by said ridges or flutings when the box is driven into the hub, and the diameter of said box through the base of said grooves 80 being less than the diameter of the entering portion of the box; substantially as and for the purposes set forth. 85

Signed at New York, in the county of New York and State of New York, this 13th day of February, A. D. 1903.

THOMAS HILL.
